UNITED STATES PATENT OFFICE.

WILLIAM A. MONTGOMERY, OF RICHLANDS, VIRGINIA.

RAIL-JOINT.

1,176,081.

Specification of Letters Patent.

Patented Mar. 21, 1916.

Application filed August 21, 1915. Serial No. 46,669.

To all whom it may concern:

Be it known that I, WILLIAM A. MONTGOMERY, a citizen of the United States, residing at Richlands, in the county of Tazewell and State of Virginia, have invented 5 new and useful Improvements in Rail-Joints, of which the following is a specification.

The present invention relates to improvements in means for connecting the meeting ends of railway rails, and the object of the invention is to simplify and improve the existing art by providing means whereby the rails may be connected between the ties.

15 Another object of the invention is to provide a joint wherein both of the rails are arranged upon a suitable support and held thereby against vertical or tilting movement, and further whereby the rails may be slid 20 longitudinally of the support to permit of one of said rails being removed if necessary, without entirely removing the other rail from the said support.

A further object of the invention is to 25 form the rails with longitudinally extending slots which enter from the base thereof at the ends of said rails and to arrange within the said slots a spline that is secured within the slots by suitable removable pins, the 30 spline being further provided with openings which register with the bolt openings in the supporting member for the rails ends.

With the above and other objects in view, the improvement resides in the construction, 35 combination and arrangement of parts set forth in the following specification and falling within the scope of the appended claims.

In the drawings: Figure 1 is a perspective view of two rails connected in accordance 40 with the present invention, Fig. 2 is a side elevation illustrating the manner in which the rails may be slid upon the support to permit of the removal of one of the rails without removing the other rail entirely from the 45 support, Fig. 3 is a transverse sectional view approximately on the line 3—3 of Fig. 1, Fig. 4 is a central vertical longitudinal sectional view through the rails at the joint thereof, Fig. 5 is a perspective view of the 50 supporting member, Fig. 6 is a perspective view of one of the rail ends, and Fig. 7 is a similar view of the connecting plate or spline.

Referring now to the drawings in detail, 55 the numerals 1—1 designate two ordinary

railway rails. Each of these rails at its end is centrally formed with a longitudinally extending slot 2, the said slot terminating below the head of the rail and communicating with the base of the rail. The web of each 60 of the rails is provided with two spaced openings, indicated by the numerals 3 and 4 respectively, the said openings passing through the slot 2. The opening 3 is smaller than the opening 4, and the said opening 4 65 is provided to receive the usual rail connecting bolt, while the opening 3 is provided to receive a removable pin 5 which is adapted to have its ends arranged flush with the sides of the rail and which is adapted to secure 70 within the alining slot 2 a connecting plate or spline 6. The connecting plate 6 in addition to being provided with openings which receive the pins 5 is provided with openings 7 which register with the bolt openings 4, and 75 preferably the plate has its opposite sides inclined or beveled from its center to its edges.

The numeral 8 designates a support which is adapted to receive the rails ends. This support includes a substantially rectangular 80 base 9 of any desired width and length and is channeled to correspond with the cross sectional shape of the rails, the said rails being slid longitudinally within the said channel so that both the webs and base portions of the rails will be firmly embraced by the walls of the channel. The upper edges of the sides 10 provided by the channel 11 are adapted to engage with the underface of the heads of the rails and preferably one of the sides, indicated by the 85 numeral 12, is of a greater thickness than the opposite side, the said opposite side being beveled from its upper edge to its connection with the base of the support proper. 90 Both of the sides are provided with registering openings 13—13 which also register with the bolt openings in the rails and passing through the alining openings are the usual bolts 14 which are provided with retaining nuts 15. The base of the support is adapted to be arranged between two of the ties upon which the rails rest, and should one of the rails become injured in any manner, it is simply necessary to loosen the spikes and slide the rails longitudinally upon the base, as illustrated in Fig. 2, the securing bolts and nuts, of course, being previously removed, and the pin connecting the spline or 100 plate 6 will be forced laterally therefrom, so 105

110

that the spline or connecting plate will be in a position to receive a new rail, as will, it is thought, be readily understood.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

1. In combination, two rails having longitudinal slots extending from their ends and entering their base portions, a connecting plate arranged within the slots, pins passing through openings in the rails and connecting plate for sustaining the plate in the openings, the said plate having openings alining with the bolt openings in the rails, a support, said support including a base member which is channeled and which has the inner faces provided by the said channel shaped to conform to the sides of the rails, and bolts passing through openings in the said sides of the support and through the bolt openings in the rails and in the connecting plate, and nuts for said bolts.

2. In combination, two rails each having its ends centrally formed with a longitudinal slot, the walls of the slot from the entrance thereof being beveled toward each other, a connecting plate having its sides beveled from its center toward its edges, and disposed within the wedge-shaped slots, pins for securing the ends of the connecting member in the slots of the rails, a support including a base provided with sides, the inner faces of the sides conforming to the shape of the rails and said rails adapted to be slid longitudinally between the sides to center the rail ends upon the support, one of the sides of the support being of a greater thickness than the other side, and the said other side being inclined from its upper edge to the base, bolt members passing through openings in the said sides, through the rails and through the connecting plate for the rails, and nut for the bolts.

In testimony whereof I affix my signature in presence of two witnesses.

WILLIAM A. ^{his} MONTGOMERY. _{mark}
